UNITED STATES PATENT OFFICE.

HENRY PEIN, OF JERSEY CITY, NEW JERSEY, ASSIGNOR OF ONE-HALF TO
AARON M. SLOSS, OF NEW YORK, N. Y.

GLASS-RINSING MEANS.

SPECIFICATION forming part of Letters Patent No. 784,755, dated March 14, 1905.

Application filed May 13, 1904. Serial No. 207,870.

To all whom it may concern:

Be it known that I, HENRY PEIN, a citizen of the United States, and a resident of Jersey City, county of Hudson, and State of New Jersey, 5 have invented certain new and useful Improvements in Glass-Rinsing Means, of which the following is a specification.

My invention relates to means for rinsing drinking-glasses, especially adapted for use 10 in connection with automatic or coin-operated liquid-dispensing apparatus.

The object of my invention is to provide simple means for rinsing glasses in which the valve-operating means will be protected 15 against accidental opening and to prevent boys from mischievously pressing down the valve with the finger and simplifying the construction of such devices.

Further objects of my invention and details 20 of construction will be hereinafter more fully pointed out, and set forth in the claims.

In the drawings forming a part of this specification, Figure 1 is a plan view of my improved rinsing means. Fig. 2 is a cross-section on the line 2-2 of Fig. 1 looking in the direction of the arrows. Fig. 3 is a side elevation, with parts broken away, of my improved rinser when in use.

As a foundation for the construction of my 25 device I may employ a suitable casing, such as 1, which may be attached to the liquid-dispensing apparatus by screws, or it may be an integral part of the cabinet. I provide a cylindrical opening, such as 2, in the top casing to receive and contain the working parts of 35 my improvements. A lower chamber 3 is employed with passage-ways 4, leading from the upper chamber, through which the waste water passes, and an under pipe 5 is connected there- 40 with to receive the discharged liquid. A pipe, such as 6, with the water-inlet connection I prefer- 45 ably attach through the drain-pipe, which passes up through the center of the casing and through the wall 7, where it is held by screw- threads or other suitable means through the instrumentality of the coupler, such as 8. I

prefer that the coupler have a larger opening than the bore of the pipe-inlet.

I provide a valve 9 for the purpose of controlling the water-spray and, as shown herein, 50 consists of a tubular piece provided with apertures 10 at the top, through which the liquid is forced, apertures 11 near the bottom, and a seat 12. The spider, preferably having four arms 13, is disposed within the casing, adapted 55 to rest loosely over the valve through the center hole 13^a and rests on a collar 9^a on the valve, which latter may be made integral with the valve or made separate and secured thereto. The opening 13^a in the spider is made 60 large enough to allow the spider to tilt, for the reasons which will appear later. A spring 14 is interposed between the wall 7 and collar 9^a, which serves to force the valve 9 upwardly, 65 thus normally closing the ports of the valve.

As a means for preventing the accidental opening of the valve, such as by unintentionally resting the hand on the same, as in former devices, I provide a central filling-piece 15, which is secured by the bolts 16 to the wall 7 70 of the casing, collars 17 on the bolts serving to hold the central piece in place, and apertures 18 are provided in the same, whereby the liquid will drain through and communicate with the discharge-pipe. As will be seen 75 in Fig. 2, the ends of the spider extend beyond the edge of the filling-piece. The space 19, which is caused by the differences in diameter of the filling-piece and the sides of the chamber 2, is of such a size as to receive the 80 tumbler 20. As will be apparent, the valve, which is slightly below the surface of the plate 15, is so protected by the latter that the accidental opening is almost impossible, and even if it were possible whatever pushes the 85 valve down would probably be large enough to deflect the spray.

When the glass is inserted in the annular opening, the spider is forced downwardly 90 evenly on all four arms, so that the valve is opened and the spray rinses the glass and passes off through the drain-outlets. Owing

to the play of the spider on the valve, the spider will not operate the latter if only one of the arms is pressed down, as might be done by mischievous boys, as it would rock on the 5 flange.

By describing my specific means for carrying out my invention I do not wish to be understood as limiting the scope of the following claims, as various changes may be made 10 without departing from the spirit and scope thereof.

Having described my invention, what I claim is—

1. In a glass-rinser, the combination of a 15 base having a top chamber, a plate, the base and plate formed with an annular recess between them, adapted to receive a tumbler, a valve below said plate adapted to control the liquid-supply, means for operating said valve 20 disposed at different points in said annular recess, whereby the said valve-operating means must be operated at the several places simultaneously.

2. In a glass-rinser, the combination of a 25 base, having a chamber, a plate, said base and plate having an annular recess for receiving a tumbler, a valve for controlling the liquid-supply, a collar on said valve, a spider fitting

loosely about said valve and resting on the collar, and having arms extending into said 30 annular recess where they are adapted to be engaged by the tumbler.

3. In a glass-rinser, the combination of a base having a top chamber, a plate, the base and plate formed with an annular recess between them adapted to receive a tumbler, a valve below said plate adapted to control the liquid-supply, a collar on the valve and a spider, having arms extending into said concentric recess, resting on said collar and adapted 40 to operate said valve.

4. In a glass-rinser, the combination of a base having a chamber 19, a superimposed plate having discharge-holes, a spray-valve controlling the liquid-supply, secured to the 45 base below said plate, a collar on said valve, a spring adapted to force said valve upwardly, a spider having radial arms extending beyond said plate, and resting on said collar.

Signed in the city, county, and State of New 50 York this 1st day of April, 1904.

HENRY PEIN.
